Primary Examiner—Louis S Zarfas*Assistant Examiner*—Eric L Goodman(74) *Attorney, Agent, or Firm*—SAIDMAN DesignLaw Group(57) **CLAIM**

The ornamental design for a portion of a mesh basket, as shown and described.

DESCRIPTION

The sole FIGURE is a perspective view of a portion of a mesh basket showing our new design.

The broken line showing of an upper portion of the front and rear walls of the mesh basket and a lower portion of the mesh basket is for illustrative purposes only and forms no part of the claimed design.
